UNITED STATES PATENT OFFICE.

MAURICE SWITZER, OF NEW YORK, N. Y., ASSIGNOR, BY MESNE ASSIGNMENTS, TO THE WILSON DISTILLING COMPANY, OF JERSEY CITY, NEW JERSEY, A CORPORATION OF NEW JERSEY.

CLOSURE AND PROTECTING DEVICE FOR BOTTLES.

1,038,023.

Specification of Letters Patent. Patented Sept. 10, 1912.

Application filed February 8, 1909. Serial No. 476,732.

To all whom it may concern:

Be it known that I, MAURICE SWITZER, a citizen of the United States, residing at New York city, county of New York, and 5 State of New York, have invented certain new and useful Improvements in Closures and Protecting Devices for Bottles, fully described and represented in the following specification and the accompanying drawings, forming a part of the same.

This invention relates to improvements in closures and protecting devices for bottles and like receptacles. In the following description, the term "bottle" will be used, 15 for convenience, to include such like receptacles.

It is the object of the present invention to provide a closure and protecting device of such a character as to preserve the lip and 20 contiguous portions of the bottle neck in a hygienic and otherwise clean condition, so that when the bottle is opened, and the contents poured therefrom, there will be no danger of such poured contents taking up 25 any impurities or foreign matter, which might be a menace to health or mar the appearance of the poured contents, and which will also be of such a character as to protect purchasers against deception by the 30 passing off on them of bottles refilled with substitutes for the materials which the bottle is supposed to contain.

As a full understanding of the improvements of the present invention can best be 35 had from a detailed description of an organization embodying the same, such description will now be given in connection with the accompanying drawings, in which—

40 Figure 1 is a vertical elevation of the upper portion of a bottle provided with a closure and protecting device embodying the present invention. Fig. 2 is a vertical section of the same. Fig. 3 is a horizontal 45 section on the line 3 of Fig. 2; and Fig. 4 is a view similar to Fig. 1, illustrating the method of removing the protecting device from the bottle preliminary to uncorking it.

Referring to said drawings, 1 represents 50 an ordinary bottle neck, which may be provided with an internal or external stopper as desired, an internal stopper 2, preferably of cork, being shown. This stopper, whether internal or external, is carefully

sterilized before its application to the bottle neck, and, after it is so applied, it is covered by a cover 3 of flexible material, preferably paper, and of such length as to extend for some distance downwardly over the exterior surface of the bottle neck so as to cover not only the stopper 2, but also the lip and contiguous portions of the bottle neck, and thus protect the stopper and such portions of the bottle neck at all times, except when the bottle is actually opened, 65 against contamination or collection of dirt or foreign matter by exposure to the atmosphere, or contact with the hands of persons who may be called upon to handle the bottle, or in any other way. Over the bottle neck thus closed by stopper 2 and covered by flexible cover 3 is placed a seal 4, between which and cover 3 is preferably interposed a cap 5 of some hard material, preferably wood. The internal diameter 75 of the upper portion of the cap 5 is slightly greater than that of the stopper 3 so as to receive not only said stopper, but also the cover 3 and a ripping strip 6, which will be presently more fully described, the lower 80 portion of said cap 5 being cut out or otherwise suitably shaped to receive a substantial portion of the upper end of the bottle neck and also provide a shoulder 7, which, by engagement with the lip of the bottle, 85 limits the downward movement of said cap and therefore of the stopper. This cap 5 not only serves to hold the cover 3, stopper 2 and (as will presently appear) ripping strip 6 in position and to give a tasteful 90 shape to the upper end of the bottle, but also, by reason of its engagement with the lip and lower portion of the bottle neck, serves to prevent accidental removal of the stopper 2. 95

The seal 4 is preferably of paper but may be of any other suitable flexible material, which, like paper, will permit gathering in of the lower end of the seal around the contracted portion of the neck of the bottle 100 below the shoulder or swell 8, and also permit the securing of such lower portion of the seal to the bottle neck, as by paste or other adhesive, which is the preferred method of so securing it although any other 105 method may be adopted which may be suitable for the purpose.

The ripping strip 6, heretofore referred

to, is of textile material, preferably tape, and consists of a narrow band, the upper end of which passes around stopper 2 and cover 3, the strip passing thence downwardly between the bottle neck and cap 5, and thence upwardly around said cap 5 and between it and the seal 4, and thence downwardly between the bottle neck and said seal 4. The lower end of the ripping strip 6 extends downwardly beyond the seal 4 and is secured to the bottle neck by a wafer 9 or other suitable seal, a portion of its lower end being left free, to be grasped by the fingers, as shown by dotted lines, Fig. 1, when it is desired to open the bottle.

The parts of this bottle closure and protecting device are applied to the bottle in the following manner. After the stopper 2 and cover 3 are placed in position on the bottle neck, the upper end of the ripping strip 6 is placed over them as shown in Fig. 2, and the cap 5 then placed over the stopper 2, cover 3 and such end of the ripping strip 6. The ripping strip 6 is then bent upwardly around the cap 5 and downwardly along the neck of the bottle to which the lower end thereof is then secured by the wafer or other sealing device 9. The seal 4 is then placed in position over the cap 5 and tearing strip 6, and its lower portion pressed around and suitably secured to the bottle neck below the swell portion or shoulder 8 thereof.

In order to open the bottle it is necessary to first break the seal 4, and this is done by the use of the tearing strip 6 in the manner shown in Fig. 4. The upper portion of seal 4 can then be readily torn away and cap 5 removed from the bottle neck, leaving the cover 3 still over the stopper 2 and upper end of the bottle neck. The person opening the bottle will then take hold of the stopper 2 and remove it from the bottle, the cover 3 still remaining over the stopper 2 and being therefore interposed between his fingers and the lip and contiguous

portions of the bottle. It is obvious, therefore, that up to the time of the removal of the stopper 2 the lip and contiguous portions of the bottle are perfectly protected by cover 3, cap 5 and seal 4 against contamination by exposure to the atmosphere or contact with the hands of the person who handles the bottle, or in any other way. It is also obvious that the tearing strip 6 not only facilitates the opening of the bottle, but also, by destroying the wafer 9 or other sealing device by which it is secured to the bottle, and the seal 4, so destroys the appearance of the bottle that it cannot be successfully reused for the purpose of passing off of any substitute for the original contents of the bottle. Another advantage of the device, due to the use of the cap 5, is that the use of a corkscrew for the removal of the stopper 2 is rendered unnecessary as the stopper may be left protruding from the bottle, as shown, sufficiently to be conveniently grasped by the fingers for withdrawal.

What I claim is:—

A bottle provided with a stopper, a cover of flexible material extending downwardly over said stopper and the lip and lower contiguous portions of the bottle, a seal inclosing said stopper and cover and secured about the neck of the bottle to prevent removal except by rupturing it, and a cap of suitably hard material interposed between said cover and seal, receiving the upper end of the stopper and suitably engaging the bottle to maintain its proper position thereon and prevent accidental removal or displacement of the stopper, substantially as described.

In testimony whereof, I have hereunto set my hand, in the presence of two subscribing witnesses.

MAURICE SWITZER.
